CHARGE FORMING AND DISTRIBUTING
MANIFOLDArlington Moore, New York, N. Y., assignor, by
mesne assignments, to Maxmoor Corporation,
New York, N. Y., a corporation of Delaware

Application April 16, 1931, Serial No. 530,518

18 Claims. (Cl. 123—122)

My invention relates to means for homogenizing the charge materials and distributing the same in such condition to the cylinders of an internal combustion engine.

5 The present invention constitutes an improvement upon the inventions shown, described and claimed in my copending applications Serial No. 513,804, filed Feb. 6, 1931, and Serial No. 514,105, filed Feb. 7, 1931.

10 The constructions disclosed in said applications, as in this, are adapted to vaporize the fuel component enroute to the engine cylinders, to maintain adequate charge velocity for the stable entrainment of the fuel component without sacrifice 15 of volumetric efficiency, to provide adequate facilities for drainage of the branches during initial operation and for vaporization of the fuel thus drained, to concentrate substantially the hottest portion of the exhaust gas stream on a central 20 portion of the intake conduit contiguous to the point of subdivision or deflection of the charge stream into the branches for causing the vaporization of fuel particles discharged through or thrown out of the charge stream at said point en- 25 route to the engine cylinders, and to render the thermal efficiency of said central heated portion substantially maximum to cause fuel vaporization at a rate to prevent accumulation of fuel in said heated portion and thermal decomposition of fuel 30 to form tarry products liable to impair the thermal efficiency of the heated portion.

The present invention has for its object to provide a construction of the character specified in which substantially all the heating for vaporization 35 of the fuel component is applied prior to the deflection of the charge stream into the branches, the charge passing through the branches being maintained cool with the fuel component in suspension without further heating.

40 Another object of the invention is to provide a construction of the character specified in which the heated and unheated parts thereof are composed of heterogeneous metals each having properties particularly adapted for the part composed thereof.

Another object of the invention is to provide a construction of the character specified in which the parts thereof are made in sections to facilitate 50 molding or casting, to afford when connected adequate compensation for strains and stresses due to the heating and cooling of the manifold, to facilitate the use of heterogeneous metals, to render the manifold more universal in its application to various types of engines or to engines

of various characteristics by simple rearrangement of port connections to engine cylinders.

Another object of the invention is to provide a construction of the character specified in which the branches thereof are substantially insulated 60 from the heated portions thereof and are composed of a material arrangement particularly adapted to promote cooling of the charge passing through the branches and to provide relative smooth interior surfaces less liable to cause re- 65 tardation of the charge velocity.

Another object of the invention is to provide a construction of the character specified in which the charge distributing passage is arranged to counteract the inertia effects on the charge there- 70 in due to conventional firing orders tending to cause unequal distribution of the charge to the cylinders.

Other objects will in part be obvious and in part be pointed out hereinafter. 75

In the accompanying drawings:

Fig. 1 is a plan of one form of manifold constructed according to and embodying my said invention;

Fig. 2 is a vertical section thereof on the line 2—2 of Fig. 1;

Fig. 3 is an enlarged transverse section on the line 3—3 of Fig. 1, the contiguous intake branch being removed;

Fig. 4 is an enlarged transverse section on the line 4—4 of Fig. 1;

Fig. 5 is a horizontal section on the line 5—5 of Fig. 4;

Fig. 6 is the inverted plan looking at the lower end of the exhaust gas conduit outlet; 90

Fig. 7 is a plan showing a modified form of branch for the intake manifold; and

Fig. 8 is a diagram illustrating the construction of the intake conduit.

The fuel vaporizing and charge distributing 95 construction embodying my said invention is adapted for use with carburetors or fuel supplying devices of various types such as with the apparatus disclosed in my copending application Serial No. 525,992, filed March 28, 1931, and while 100 the manifold is particularly adapted for distributing charge mixtures containing fuel of high volatility, such as gasoline, charge mixtures containing less volatile fuels, may be as effectively distributed thereby in homogeneous admixture with 105 the air.

When three port manifolds such as herein shown as an example of one embodiment of the invention, are employed, there is a tendency for the center port to receive a heterogeneous charge 110

whereas one end port receives a rich charge and the other end a lean charge. This condition is aggravated because the incoming charge picks up condensed fuel from the intake manifold walls, 5 and particularly in the longer branches where the tendency to condense is greater. The condensation or loading up of fuel in the intake manifold usually takes place during periods of low speed operation. The accumulated or condensed 10 fuel swept into the engine cylinders, especially when the throttle is opened wide, causes waste of fuel, oil dilution, non-uniform distribution with temporary over-richness of the mixture in certain 15 of the cylinders, and other detrimental effects, resulting especially in roughness of engine operation. While various expedients have been resorted to in order to obviate these defects, none of them has proved very successful.

In my invention I rely upon the suitable application of heat to the intake conduit whereby the fuel component of the charge is completely vaporized and maintained vaporized enroute to the intake ports, and the maintenance of this condition is preferably supplemented or helped 20 by providing branches of progressively decreasing cross-section such as disclosed as a feature of the intake manifolds of said applications Nos. 513,804 and 514,105 and of my application Ser. No. 234,417, filed November 19, 1927, thereby promoting uniform distribution to the intake ports with resulting smooth, powerful and economical 25 engine operation. The invention is adapted for intake manifolds having two, three, four or more ports.

Referring to the drawings, the intake manifold 10 (the form illustrated being of the down-draft type) is preferably located above the exhaust manifold 12, being associated therewith for heating purposes. The charge mixture passes 30 into the manifold through the central neck portion or descender 14 formed integrally with the exhaust manifold and into the branches 16 and 18 and out through the elbow outlets or end portions 20 and 22, the central cylinders being 35 supplied by the shorter central branch 24. The branches 16 and 18 are preferably separately formed and are detachably connected to the central portion 14 as hereinafter more fully described.

The intake manifold 10 illustrated as one example, is for a six cylinder engine having intake ports in sets of pairs in the cylinder block. With cylinder blocks designed for receiving only two intake manifold branches, the branch 24 is omitted. With the form shown, neck 14 leads 40 downwardly to communicate with the branches at substantially the middle of the manifold and immediately above the entrances to its branches, and at this point a distributing chamber 26 is provided from which the mixture is supplied to 45 the manifold branches 16, 18, and 24.

The branches 16 and 18 have entrances 28 and 30 thereto from the chamber 26 of enlarged areas as compared to the area of the openings 20, 22 and 24, and of reduced areas as compared to the 50 cross-sectional area of the neck 14, and their cross-sectional area gradually decreases towards the end portions 20 and 22 to cause an increase in the velocity of the fuel charge as the same approaches the elbows, and in this way the charge mixture 55 can be delivered to the straight-in passages 20 and 22. The cross-sectional area of said branches 16 and 18 at the elbows 20 and 22 is substantially the same as the cross-sectional area of the entrance 24.

55 The branches 16 and 18 each preferably com-

prises a semi-cylindrical upper portion 32 of substantially uniform cross-section from the inner end thereof to the elbow thereof, and preferably horizontal, and a lower portion 34 at the base thereof merging into the upper portion 32 and likewise extending from the inner end of the branch into the elbow thereof and gradually decreasing in cross-sectional area or depth towards each elbow, the upper portion 32 forming the major part of the branch and the lower portion 34 the lesser part. The portions 34 jointly with the upper portions 32 form passages providing the relatively large entrances 28 and 30 and gradually decreasing in cross-sectional area to said elbows 20 and 22.

The desired inclination of the floor of the intake conduit branch and the tapering thereof as a whole is obtained as illustrated in Fig. 8, representing successive cross-sections taken on the lines *x*, *y* and *z* of Fig. 1. The cross-section at the elbow is a circle *x* having a radius *r*.

The cross sections of the upper portion 32 from the elbow inwardly are partial circles *x'*, *x''* having the same radius *r*, the centers *c* of the several circles lying on the same horizontal line. The cross sections *x'*, *x''* however are enlarged progressively towards the inner end of the branch, the lower portion 34 having cross-sections conforming to partial circles *a*, *b*, having the same radii *r* and described about centers *c'*, *c''* located vertically below the centers *c* and progressively increasing in distance therefrom, the partial circles *a*, *b*, merging with the partial circles *x'*, *x''*.

By progressively enlarging the general contour of the branch at the bottom, the branch is made 110 to incline downwardly towards the center of the manifold at a substantial angle for drainage purposes, as indicated at *d*, Fig. 8. At the same time the branch passage as a whole varies in cross section at a rate determined solely by the variations in cross section of the relatively smaller lower portion 34, the rate of variation in cross section of the branch passage as a whole being less than the rate of variation in cross-section of the lower portion 34. The lower portions 34 120 therefore provide sufficient inclinations for drainage and effect relatively slight progressive restriction of the branches to cause acceleration ratio proportional to distance traveled by the charge materials to effect uniform delivery 125 through all ports.

The branches 16 and 18 are cast as separate open ended units or members with flange portions 36 contiguous to their inner ends adapted to register or fit corresponding bosses or portions 38 formed on the central portion 14 and disposed about the entrances or openings 28 and 30 therein. The inner portions of the bosses 38 are preferably recessed, as indicated at 40, to receive the projecting end portions 42 of the 135 branches, the parts interfitting to form right angle joints with the branch passages registering with the entrances 28 and 30 to form continuations thereof. The branches are secured in position by means of the bolts 44 extending 140 through the flanges 36 into the bosses 38, gaskets 46 being interposed between the flanges and the bosses for producing a tight joint. The gaskets 46 are preferably composed of a material thermally insulating the branches from the central 145 portion 14.

The exhaust manifold 12 is preferably of the type in which the exhaust gases are conducted from the cylinders toward the middle and out through a central outlet 48, the branches 50 and 150

52 thereof having openings 54 and 54a adapted to register with the exhaust passages of the cylinder block. Each opening 54a is long enough to register with two passages of the cylinder block, 5 and is of reduced depth to reduce expansion of the hot gases entering the exhaust manifold and thereby preventing cooling.

In the present embodiment of the invention the exhaust gas manifold branches are disposed 10 in spaced relation to the intake branches, providing air gaps 56 therebetween, which, as shown at Fig. 2, increases in width towards the outer ends of the manifold.

The intake conduit 10 at the junction of the 15 branches thereof opposite the neck 14 is provided with a wall portion 58 extending downwardly into the exhaust passage coaxially with and in spaced relation to the walls of the outlet 48, i. e., substantially at the point where the two exhaust gas 20 streams unite, which is substantially the hottest part of the exhaust gas. The upper end of the portion 58 opens into the intake manifold and the lower end thereof is closed by a dome shaped member or wall portion 60 in spaced relation 25 thereto to form a substantially annular chamber 62 opposite the inlet 14 at the point of subdivision of the charge mixture stream but lying substantially beyond the path of travel thereof, the upper end of the dome 60 preferably lying entirely below the plane of the intake branches. 30

The portion 60 is preferably separate from the portion 58, the former preferably being composed of a material of high heat conductivity, such as copper. The interior 62a of the portion or member 60 is exposed to the hot exhaust gases, the member preferably having means formed to insure positive circulation of the hot exhaust gases therethrough.

This means in the present embodiment of the 40 invention includes a deflector or baffle 64 forming an integral extension of the relatively massive lower portion 66 which forms a heat reservoir integral with the dome 60 and lies within the exhaust gas outlet 48. The baffle 64 extends 45 into the chamber 62a, substantially bisecting the same and terminating short of the top thereof. This forms a return bend passage having an entrance 68 through which a portion of the hot exhaust gases are bypassed from the outlet portion 48 and directed into contact with the upper portion of the dome. The bypassed exhaust gases pass out directly to atmosphere through an outlet 70 at the opposite end of the return bend passage 62, thereby accelerating the circulation 50 and keeping the dome heated to a maximum. The dome 60 may be knurled or roughened to transfer heat to the fuel at maximum rate and reduce film deposit. The member 60-66 is preferably threaded into portion 58, as indicated at 55 72.

The exhaust manifold 12 is arranged to supply heat to the neck 14 of the intake manifold by surrounding the neck with a jacket extension 74 of the exhaust manifold, which jacket is vented 65 directly to atmosphere through outlet opening 76 at the upper end thereof to insure positive circulation of hot exhaust gases through the jacket 74.

The exhaust gases discharged through the outlet openings 70 and 76 are carried to a remote point through a common conduit 78. The conduit 78 at its upper end has a flange 82 adapted to engage the portion 84 about the outlet 76 and to be secured thereto by screws 86. The conduit 78 extends downwardly substantially parallel with the descender 14 and with the main exhaust

discharge outlet 48. The exhaust gases discharged through outlet opening 70 are conducted through a transverse conduit or pipe 88 communicating with and connected to the pipe 78 at 90. The portion 88 has a telescoping end portion 92 extending into the outlet opening 70, and a flange 94 for securing the same to the portion 48 by screws 96. The axes of the outlet openings 70 and 76 are disposed at right angles to each other so that the exhaust member 78-88 can be readily connected.

The neck 14 is terminated in a sharp angle, as indicated at 98, to shed off any liquid fuel from the neck wall into the air stream.

The annular well 62 between the walls 58 and 60 is subject on both sides to the most concentrated heat from the exhaust gases. The massive metal member 66 of copper, catalytic alloys, or the like, serves as a thermal reservoir for uniform supply of heat to the dome 60 by conduction.

An air bleed through passage 100 serves to supply air for scavenging fuel in crucible 62 to facilitate the returning of the vapors into the intake during engine operation, or if liquid fuel should 100 accumulate in the well 62 it can run out through said passage 100.

The fuel, when gaseous injection is employed for blasting the same into and through the air stream in neck 14, is very thoroughly pulverized 105 by reason of its greater velocity, and by reason of its resulting great surface exposure to the air absorbs heat therefrom very rapidly. Rapidity of heat absorption is of utmost importance because of the extremely short interval of time 110 available and which is longest with the slow charge travel during engine idling and shortest with the high speed charge travel encountered at full power operation. Heavy fuel, when used, is capable of taking up more heat than on operation 115 with lighter and more volatile fuels. The heat of the charge is thus reduced so as to favor having high density charge productive of good volumetric efficiency, and the fuel is in large part put into such condition—gasified and/or vaporized and/or in fogged or like highly divided state, that it is suspended in and carried along with the air stream without condensation or deposition on the conduit walls as the air stream branches or changes direction on its way to the 120 engine cylinders.

The stream of blasted fuel, or fuel carried by the air from an ordinary carburetor, usually contains some fuel portions or droplets heavy enough to continue their substantially straight line 130 travel without material deflection with the moving air. Unless given a liberal application of heat, this fuel portion would wet and load up the walls of the intake manifold.

By changing the direction of the intake manifold passage in the neighborhood where the blasted or inertia impelled heavier fuel particles strike the conduit walls, I can carry the lighter fuel particles thoroughly suspended in the air stream towards the engine cylinders with the air stream, 140 and by applying heat of the exhaust gases to the intake conduit walls, I am enabled to secure a selective application of heat to vaporize and suspend this fuel without undesirably heating the air of the charge.

The illustrated mode of securing such effect is by directing the fuel blast or fuel charge mixture downwardly in the intake manifold neck 14, which at the bottom branches to each side, while applying heat of exhaust gas at 74 without such 150

neck, thus providing a hot surrounding wall adapted to be contacted by and apply heat to the heavy particles of fuel spreading to the outer region of the blast fuel stream, and by providing the hot 5 cup or crucible 62 in line with the discharge end of the neck 14, where the convex heated portion 60 also radiates heat upwardly to the charge passing to the cylinders, or is struck by and supplies vaporizing heat to the heavy fuel particles projected thereon.

Inasmuch as the exhaust gas from all the exhaust ports is directed into the vicinity of the crucible 62, the crucible is subjected to the maximum temperature available. The annular crucible is in contact at both sides with the exhaust gas, and provides a doubly extended surface, compared to the surface of an ordinary non-annular cup, for heating the projected fuel, the heating effect being augmented by the positive 10 deflection of a portion of the exhaust gases into the interior of the dome 60. By disposing the convex dome 60 in the path of the downwardly projected fuel, the impact of the fuel particles thereon cause the particles to be reflected therefrom or to be deflected without tending to conglomerate or accumulate thereon, as such particles would be likely to do if the surface 60 were flat, an extended downwardly curving surface being provided along which the fuel particles 15 20 25 30 35 40 may gravitate, until vaporized, thereby enhancing vaporization or fuel nebulizing without substantial accumulation of liquid fuel in the bottom of the crucible 62. The vaporizing effect is also assisted by the provision of a down-draft manifold in which the fuel particles are caused to positively gravitate in the direction of air flow into the crucible and onto the dome, the incoming particles being subjected to air passing through the opening 100 and moving in the opposite direction.

The temperatures available with my manifold, particularly at the higher speeds, are sufficient to cause the fuel particles to assume the spheroidal state, evidenced by the fact that the fuel does not form tarry or other solid precipitates within the crucible 62 and the vapor produced is substantially dry and less liable to condense.

Sudden changes from heavy to light loads are accompanied by a flow of heat from the massive 50 member 66, rendering available heat for re-stabilizing the mixture when inertia effects on fuel flow are prevalent, and particularly when the engine is brought down to idling from loads.

Extraneous heat for vaporizing and homogenizing the fuel component is thus applied in an efficient manner prior to the deflection of the charge into the branches, and during the downward travel thereof. The cross-sectional area of the neck 14 is preferably greater than the mean cross-sectional area of the branch to retard the velocity of the charge during the vaporizing stage, and the length of the neck 14 is such that substantially complete vaporization of the fuel 55 60 65 70 component is effected by the several heating means 60 and 74 during the time interval of vertical travel of the charge, thereby forming a stable homogeneous mixture, the stability of which is enhanced because of the spheroidizing effect of the crucible 62. By applying preliminary heating or part of the heating to the neck 14 through jacket 74, localized wetting down of the vertical passage due to cold walls is also prevented, and washing down of deposited fuel into 75 the branches to cause non-uniform distribution

to the cylinders or other detrimental effects cannot occur.

The heating capacity of the dome 60 depends on the area of the surface thereof and on the flow of exhaust gas through the interior thereof. The diameter of the dome 60 is preferably made greater than the diameter of the passage through the neck 14 in alignment with said dome so that projected fuel particles passing from the neck 14 are sure to contact with said dome to complete the vaporization.

The application of extraneous heat substantially in the locality where the fuel is introduced into the air in a highly comminuted or atomized state, and before such fuel condenses on the wall, facilitates vaporization, and the application of heat for vaporizing is accomplished here without appreciably expanding the charge, because the heat absorption by the fuel is then high relative to the heating. The dome 60 has a high heat radiating capacity because of its thinness and composition but the heating action thereof does not appreciably affect the charge density because the dome lies substantially out of the path of travel of the charge and the heat absorption is high.

By the combined effect of the contact of the fuel particles upon these wall surfaces, and the efficient application of heat thereto, the homogeneous suspension of the fuel in the air is completed, without undue air heating and loss of volumetric efficiency through air heating and charge density reduction.

To maintain the homogeneous suspension of the fuel in the air so attained, I now keep the 110 sectional area of the intake manifold branches, and, therefore, of the moving charge stream as low as practicable without unduly restricting charge flow, thus keeping the charge moving rapidly and avoiding any slowing up or expansion of 115 the charge material on its way to the engine cylinders, which would be productive of condensation, and I also preferably progressively increase the charge velocity during such travel, as by progressive reduction of the cross-sectional area of 120 the manifold branches from the common neck portion thereof to the engine cylinders.

The intake branches 16 and 18, being separated from the exhaust manifold 12 by gaps 56, are substantially entirely insulated from the exhaust 125 manifold by the surrounding air, or other cooling medium, so that no heating is applied to the charge in the branches after deflection of the charge thereinto, whereby a cool dense charge is caused to enter the cylinders in a homogeneous 130 condition. The intake branches 16 and 18 because of their detachability can be and are preferably composed of a material of relatively high thermal conductivity, such as cast aluminum, capable of rapidly conducting away surplus heat 135 to cause the charge to become cool and dense, or to maintain such charge in that condition. By the use of a material, such as cast aluminum, the interior walls of the manifold branches can be made much smoother than where cast iron is used, reducing skin friction tending to retard the charge velocity so that fuel precipitation is less liable to occur.

The result is that a cool dense charge is delivered to the straight-in ports 20 and 22 of the lateral branches 16 and 18 as effectively as the delivery thereof to the intermediate port 24, the charge being uniformly distributed in a homogeneous condition to the cylinders in substantially 140 145 150

the proportions for which the carburetor or other fuel supplying device is economically set.

The floors 34 taper from least at the outer ends of the intake manifold branches to largest depth 5 where they lead down into the annular well 62.

The decrease in section of the intake manifold speeds up the charge as it travels to the engine cylinders thereby opposing any tendency of fuel particles to deposit on the walls.

10 By venting the annular well 62 to the atmosphere at its bottom through passage 100 any liquid fuel which may run back from the branches and accumulate in well 62, as for example, at starting, or upon pumping in extra fuel 15 for acceleration, will not simply boil or distill off, but can either run out through such vent, or, in case the intake depression is relatively high, be carried along upwardly as vapor with air admitted through the opening 100.

20 That the hot wall surfaces are of sufficient area and mass to supply vaporizing heat to the relatively large quantity of liquid fuel blasted or otherwise projected thereagainst during full power operation insures plenty of heat being 25 available when the same walls are used for communicating heat to the fuel when supplied in smaller quantities, even though the temperature of such walls is then lower. Owing to the heat available through the walls of the crucible 62, 30 vaporization of fuel is accomplished without the formation of tarry products liable to reduce the thermal efficiency thereof because of the insulating effects of such tarry formations.

The charge so produced in passing to the cylinders through the branches 16 and 18 remains in a homogenized state, without substantial precipitation of fuel, due to the efficient vaporizing and spheroidizing action imparted thereto prior to the entrance of the charge into the branches, 40 thereby rendering unnecessary the application of additional heat to the same in the branches, so that the charge, being unheated, passes to the cylinders in a relative dense state productive of maximum power.

45 The thermal vaporizing effect of the manifold may be augmented by discharge of the fuel into the region of intake depression at the engine side of the throttle as set forth in my said application Serial No. 525,992, the manifold being equally efficient, however, with conventional carburetors, such as those connected below the throttle. The manifold can be adapted to meet any engine or fuel requirement by slight variation in the thermal and other relationships of the 55 parts.

At Fig. 7 is shown a modified form of intake manifold branch 16a adapted to replace the left hand branch of Fig. 1 and having means incorporated therewith to counteract somewhat the forces of inertia that are caused by conventional firing orders. These inertia effects have a tendency to ram more material through the end outlet of the manifold towards the back of the engine than the front. For instance, observation 65 shows that cylinders Nos. 5 and 6 tend to get more fuel than cylinder No. 1 of a six cylinder engine. To overcome or counterbalance this effect the straight-in port 20a to cylinders 5 and 6 is disposed at right angle to the branch 16a to subject the charge to an abrupt turn, and a chamber 102 is disposed beyond the port 20a in line with the branch 16a and forming a continuation thereof. The depth of said extension 102 can be 70 adjusted by adjustment of the threaded plug 104. The chamber 102 acts as buffer receiving the

thrust of the charge due to the inertia effects so that a normal charge tends to enter the port 20a. The other branch of the manifold remains like that shown at Fig. 1, one branch only being provided with such extension 102.

80 By my invention, the application of heating to the charge is restricted to the central portion of the manifold, as the charge travels downwardly at a somewhat retarded velocity. No heat is applied to the branches which are con-

85 structed to maintain the charge cool and also to maintain sufficiently high velocity thereof to retain the fuel in suspension. The neck or central portion 14 of the intake manifold and the exhaust manifold 12 are formed integrally preferably of cast iron. The use of cast aluminum is preferable for the branches because of its relatively greater thermal conductivity and capability of being made smooth. The branches are

90 therefore made detachable or separate from the cast iron portion to enable the utilization of such heterogeneous metals. Making the branches separate facilitates molding or casting of the parts and allows access to the interior thereof for machining the inner surface. Separate or

95 detachable branches may be supplied in various shapes or sizes to enable the fitting thereof to various types of engines and to engines of different characteristics. Charge distribution varies with the engine characteristics, and this

100 method of construction enables the particular branch to be adapted which suits the individual needs. The jointed connection at the inner end of the branch also provides compensation for strains and stresses due to the heating and cool-

110 ing of the manifold, this type of construction being less liable to crack than an integral construction. The aluminum branches 16 and 18 are separated from the exhaust conduit by the air gaps 56 and are insulated from the heated

115 portion by the gaskets 46. The result is that the charge in the branches becomes or remains cool and dense, obviating the danger of overheating the charge, so as to impair the volumetric efficiency.

120 Having thus described my invention what I claim and desire to secure by Letters Patent is:

1. An intake manifold comprising an inlet portion including heating means and composed of a material capable of resisting the heating, and 125 branches composed of a material of relatively high thermal conductivity detachably secured to said inlet portion at opposite sides thereof.

2. An intake manifold comprising an inlet portion, and branches detachably secured to said inlet portion at opposite sides thereof, said branches having upper portions of uniform cross-section and lower portions inclined downwardly towards said inlet portion and decreasing in cross-section towards the outer ends of the branches.

130 3. An intake manifold comprising an inlet portion including heating means and composed of cast iron, and cast aluminum branches secured to opposite sides thereof.

135 4. A charge forming and distributing manifold comprising an intake conduit having a central inlet portion and branches, and an exhaust conduit, said inlet portion and said exhaust conduit being formed of a metal having a relatively high melting point and being in thermo-conductive relation to each other, and said branches being composed of a different metal of relatively high thermal conductivity.

140 5. A charge forming and distributing manifold comprising an intake portion having a cen-

- tral neck, and a hollow dome in alignment with said neck, means for bypassing exhaust gas into contact with the walls of said neck and into the interior of said dome, and a common conduit 5 venting said bypassing means at the neck and the dome for discharging the exhaust gas directly to atmosphere.
6. A charge forming and distributing manifold comprising a heated central inlet neck portion, 10 and lateral branches, the cross-sectional area of the heated central inlet portion being greater than the cross-sectional area of the branches to retard the charge velocity during the heating thereof.
- 15 7. A charge forming and distributing manifold comprising a heated central inlet portion, and lateral branches, the cross-sectional area of the heated central inlet portion being greater than the cross-sectional area of the branches to retard 20 the charge velocity during the heating thereof, and the cross-sectional area of the branches decreasing towards the outer ends thereof to accelerate the charge velocity.
8. A charge forming and distributing manifold 25 comprising a heated central inlet neck portion, and lateral branches, the cross-sectional area of the heated central inlet portion being greater than the cross-sectional area of the branches, and said branches serving to cause the charge therein to be relatively cool.
- 30 9. A charge forming and distributing manifold comprising a central inlet neck portion having heating means and lateral branches, the cross-sectional area of the heated central inlet portion being greater than the cross-sectional area 35 of the branches, and said branches being substantially insulated thermally from said heating means and composed of a metal of relatively high thermo-conductivity.
- 40 10. A charge forming and distributing manifold comprising an intake conduit having a central neck portion and lateral branches, a jacketed passage around said neck portion, an exhaust conduit communicating with said jacketed passage, an annular crucible disposed in alignment 45 with said neck portion and extending into the exhaust conduit, said crucible including a member having a convex surface facing said neck portion, means for causing circulation of exhaust 50 gas into said convex member, and means for venting said jacketed passage and said dome directly to atmosphere.
11. A charge forming and distributing manifold comprising an intake conduit having a central neck portion and lateral branches, a jacketed passage around said neck portion and an exhaust conduit in thermal conductive relation to the central portion of the intake conduit opposite 55 said neck portion and communicating with said jacketed passage, said exhaust conduit being separated from said intake branches.
- 60 12. A charge forming and distributing manifold comprising an intake conduit having a down-draft inlet portion and lateral branches, a jacketed passage about said inlet portion, an exhaust conduit having a central portion in thermo-conductive relation with the central portion of the intake conduit opposite said down-draft inlet por-

tion, and communicating with said jacketed passage, the branches of said exhaust conduit being separated from the intake branches.

13. A charge forming and distributing manifold comprising an intake conduit including a central portion and branches, and an exhaust conduit formed integrally with said central portion, said integral part being composed of a metal having a relatively high melting point, and said branches being separately formed of a different metal of relatively high thermal conductivity, and disposed in separated relation to the exhaust conduit.
14. A charge forming and distributing manifold comprising an inlet neck portion and branches, and heating means about said neck portion and in alignment therewith beyond the point of deflection of the charge into the branches, said neck portion having a cross-sectional area greater than that of the branches to slow up charge travel through the heated neck portion and effect delivery of unvaporized fuel particles to the aligned heating means.

15. A charge forming and distributing manifold comprising an intake manifold, and an exhaust manifold, the central portion of said intake manifold and said exhaust manifold being composed of a heat resisting metal and being formed integrally with each other in thermo-conductive relation, the outer portions of said intake manifold being separately formed and connected to said central portion in spaced relation to said exhaust manifold, and being composed of a metal of greater thermal conductivity than said heat resisting metal.

16. A charge forming and distributing manifold comprising an intake conduit having a jacketed neck portion and a heat transfer portion in alignment with said neck portion, and an exhaust conduit having a main discharge outlet, 115 and communicating with said jacketed portion and said heat transfer portion, said jacketed and heat transfer portions being each vented directly to atmosphere to insure positive circulation of exhaust gas therethrough.

17. A charge forming and distributing manifold comprising an intake conduit having an intermediate jacketed inlet portion, and a hollow heat transfer portion in alignment with said inlet portion, and an exhaust gas conduit having 125 an intermediate outlet and communicating with said jacketed inlet portion and with the interior of said hollow heat transfer portion, said jacketed portion and said hollow heat transfer portion each having a separate vent therefrom to atmosphere for the discharge of exhaust gas therefrom.

18. A charge forming and distributing manifold comprising an intake conduit having a jacketed inlet portion, a hollow heat transferring dome 135 portion in alignment with said inlet portion, an exhaust conduit having an outlet and including means for bypassing the exhaust gases through said jacketed portion and through the hollow interior of said dome portion, said bypassed gases 140 being vented from each of said heated portions directly to atmosphere.

ARLINGTON MOORE.
